UNITED STATES PATENT OFFICE.

JOHN C. AYLING, OF SPRINGFIELD, ILLINOIS.

KITE.

1,180,224.

Specification of Letters Patent.

Patented Apr. 18, 1916.

Application filed July 1, 1915. Serial No. 37,564.

To all whom it may concern:

Be it known that I, JOHN C. AYLING, citizen of the United States, residing at Springfield, in the county of Sangamon and State 5 of Illinois, have invented certain new and useful Improvements in Kites, of which the following is a specification, reference being had therein to the accompanying drawing.

This invention relates to kites and has for 10 its principal object the production of a foldable kite which may be easily dis-assembled and folded to a closed position so as to occupy only a minimum amount of space when the same is not in use.

15 Another object of this invention is the production of a kite wherein the cross stick is pivotally and slidably mounted upon the vertical stick so as to be easily swung to an extended position when it is desired to set 20 up the kite, or which may be folded upward with the vertical or main stick when the kite is not in use.

Another object of this invention is the 25 production of a kite wherein the sticks are provided with cross notches at their ends so as to receive the several cords which carry the paper or cloth wing or face of the kites as well as the bow cord and trimmings used in connection therewith.

30 With these and other objects in view this invention consists of certain novel combinations, constructions, and arrangements of parts as will be hereinafter fully described and claimed.

35 In the accompanying drawings: Figure 1 is a front elevation of the kite as constructed in accordance with this invention. Fig. 2 is a detailed perspective view of the frame work of the kite in a set-up position, the 40 wing and trimmings being removed. Fig. 3 is a fragmentary horizontal section through the sleeve which carries the cross section. Fig. 4 is a fragmentary vertical section through a portion of the kite illustrating 45 the manner in which the sleeves support the cross stick. Fig. 5 is a detailed perspective view of the sleeve. Fig. 6 is a fragmentary sectional view through one end of the cross stick illustrating the manner in which the 50 cords are carried by the notches thereof. Fig. 7 is a horizontal fragmental section through one end of the cross stick illustrating the manner in which the cross stick is bowed rearwardly. Fig. 8 is a detailed 55 perspective view of one end of the cross stick illustrating the notches therein. Fig. 9 is

a fragmentary perspective view of one end of the vertical or main stick showing the notches therein. Fig. 10 is a detailed perspective view of the reinforcement used upon 60 the face or wing of the kite, illustrating the manner in which the flying cord may be attached thereto, the wing or face being shown in section.

Referring to the accompanying drawing 65 by numerals it will be seen that the frame of the kite comprises a vertical upright or main stick 1 having cross notches 2 and 3 formed in its end portions so as to intersect each other, as is clearly shown in Figs. 2 70 and 9. The sleeve 4 which is formed of a blank sheet of metal is bent so as to form a rectangular structure in which there is formed an opening 5. The headed tack 6 is passed through this opening 5 and has its end clamped as shown at 7 so as to fixedly retain this sleeve 4 in pivotal engagement with the upright 1. This sleeve 4 is bent so as to have its free edges 8 abutting against each other, while the end portions thereof are bent as shown at 9. The cross stick 10 is carried by this sleeve 4 so as to be pivotally and slidably mounted upon the vertical upright or main stick 1, adjacent the upper portion thereof. This cross stick 10 is also 80 provided with cross notches 11 and 12 formed in its end portions and constructed so as to intersect each other, similar to the cross notches formed in the upright or main stick 1. It will therefore be seen that when 90 the device is not in use the cross stick may be swung, thereby causing the sleeve 4 to pivot upon the tack 6 and then be drawn so as to rest throughout its entire length upward with and upon the main stick 1. When, however, it is desired to fly the kite, 95 the cross stick may be swung so as to extend at right angles to the main stick and then moved so as to slide through the sleeve 4 and extend for equal distances upon either side 100 of the main stick 1, as shown in Figs. 1 and 2. A cord 13 may then be passed around the outer ends of the sticks 1 and 10 so as to rest within the notches 3 and 12 of the sticks 1 and 10 respectively as shown in Fig. 105 2. This cord 13 carries the paper or cloth face or wing 14 which is positioned upon the cord and secured thereto by being bent around the cord as shown at 14' and pasted thereon in the usual manner now employed 110 in fastening the face or wing of a kite to its supporting cord. The face 14 is cut away

as shown at 15 so as to allow free access to the cord 13 at the point where the same is to be carried by the sticks 1 and 10 whereby the wing or face may be quickly attached or detached to the sticks 1 and 10 as the occasion may require. It is, of course, obvious that at these corner portions the wing may be reinforced as shown at 16 to strengthen the same and prevent the tendency thereof of becoming torn when the same is being attached or detached. After this wing has been attached it is desirable to fold the kite rearwardly so that the air currents which will strike upon the face of the kite may pass around its side portions and retain the same in the air, inasmuch as the curved structure of the kite will prevent the undue banking of the atmosphere at one side of the kite rather than the other, and thus cause the kite to glide sidewise and then finally fall. This is overcome by the pivotal bow cord 17 which has a knot 18 in one end so that the cord may pass through one of the notches 11 of the cross stick 10, while the knot will prevent its accidental withdrawal therefrom. The cord 17 is provided with a plurality of knots 19 adjacent its end so that the cord may pass through the opposite notch 11 of the cross stick 10 opposite to the one adjacent which the knot 19 is supported. By providing a plurality of knots the degree of bowing the cross stick 10 may be increased or reduced as desired, and therefore, by passing this cord across the rear portions of the kite and bowing the stick 10 as set forth the air will strike upon the curved forward face of the kite and will cause the same to ride evenly in the air when the same is being flown.

40 The face or wing 14 is provided with a pair of short slots 20 formed at its central portion so as to be in alignment with the upright or main stick 1. These slots are reinforced by means of reinforcing strips 21 which are pasted or otherwise secured to the wing 14 upon each side thereof so as to allow the slots 22 of this reinforcement to register with the slots 20 formed in the wing or face 14 whereby the flying cord 23 may pass therethrough and tied in engagement with the main stick 1 as shown at 23'. After the wing or face 14 has been attached to the sticks 1 and 10 as hereinbefore set forth the cord 23 may be attached so that a second cord, not deemed necessary to be herein disclosed may be attached to this cord 23 for holding the kite as the same is being flown. In order to fly with a more pleasing effect and for beautifying the kite an endless cord 24 may be passed around through the notches 3 and 12 of the sticks 1 and 10. This cord 24 is adapted to carry the trimming or edging 25 which is secured thereto in any suitable manner. It is of course obvious that by passing this endless cord 24 around

through the notches as set forth, it will engage the bow cord 17 adjacent its ends for preventing its accidental displacement when the kite is in use.

From the foregoing description it will be seen that a very simple and durable kite has been produced which is so constructed as to be easily dis-assembled and folded to a closed position so as to be easily carried about when the same is not in use, in which the cords are carried within notches so formed as to prevent the accidental displacement of the cords. Furthermore, the bow of the kite will cause the same to have an even air pressure upon its forward portions when the same is being flown, whereby the entire construction will present a simple and efficient kite which is durable in construction, inexpensive in manufacture, and possesses all the qualities necessary to its efficient flying. It is, of course, obvious that the face or wing 14 may be provided with adhesive material adjacent at side edges so that when the kite is assembled this adhesive material may be moistened, whereby when the side edges are passed around the cord 13 the adhesive material will cause the portions of the body adjacent the side edge to become attached to the main body portion or wing, thereby positively and fixedly retaining the wing or face in engagement with the cord. It is further obvious that any suitable reinforcing means, such for instance as cord may be wound about the central portions of the cross stick and also the main or vertical stick for the purpose of forming reinforcement for the sleeve 4 so that in case the sleeve 4 is injured this reinforcing means will retain the cross stick in its correct position upon the main or vertical stick. 105

What is claimed is:

1. A kite of the class described, comprising a main stick, a cross stick pivotally and slidably mounted upon said main stick whereby when the device is not in use it may be folded to a closed position so as to allow the cross stick to rest upon and extend parallel with the main stick, and a wing or face detachably mounted upon said sticks. 110

2. A kite of the class described, comprising a main stick, a sleeve pivotally mounted upon said main stick and adjacent one end thereof, a cross stick slidably mounted upon said sleeve whereby when the device is not in use the sleeve may be swung so as to extend in the same direction as the said main stick, whereby the cross stick will rest upon said main stick at which time the stick will move upon said sleeve so as to rest throughout its entire length upon said main stick, and a face or wing detachably mounted upon said sticks. 120

3. A kite of the class described, comprising a main stick, a hollow sleeve, means passing through said hollow sleeve and en- 125

gaging said main stick for pivotally securing said sleeve upon said main stick, a cross stick slidably mounted through said sleeve, a face or wing detachably mounted upon said sticks, said wing being capable of being detached when the device is not in operation, at which time the said sleeve may be swung so as to allow the said cross stick to be moved so as to rest throughout its entire 10 length upon said stick.

4. A kite of the class described, comprising a main stick, a cross stick pivotally and slidably carried upon said main stick whereby said sticks may rest upon each other 15 when not in use, said sticks provided with notches at their outer ends, a face or wing positioned upon the forward face of said sticks and provided with a supporting cord detachably carried within said notches, and 20 means for bowing said cross stick rearwardly so as to provide a curved forward face for the kite for facilitating its flying.

5. A kite of the class described, comprising a main stick, a cross stick pivotally and slidably carried by said main stick whereby 25 said sticks may rest upon each other when not in use, said sticks provided with notches at their outer ends, a wing or face positioned upon said sticks and provided with a supporting cord detachably carried by said 30

notches, and a bow cord detachably mounted upon said cross stick for bowing the cross stick rearwardly whereby the forward face of the kite will be curved so as to facilitate the flying of the kite.

6. A kite of the class described, comprising a main stick, a cross stick pivotally and slidably mounted upon said main stick, said sticks being provided with cross notches at their ends, a wing or face positioned upon 40 the forward portions of said sticks and provided with a supporting cord detachably fitting within a plurality of said notches, a bow cord provided with knotted ends detachably carried by a plurality of the remaining notches whereby the said cross stick may be bowed rearwardly so as to provide a curved forward face for facilitating the flying of the kite, and a trimming cord passing around through a plurality of the 45 notches in said stick so as to fit upon the cord of said face or wing, said trimming cord also passing around said bow cord between its ends for preventing its accidental displacement, and means attached to said 50 main stick and passing through said face or wing for flying the kite.

In testimony whereof I hereunto affix my signature.

JOHN C. AYLING.
